UNITED STATES PATENT OFFICE.

ARTHUR M. SMITH, OF CLEVELAND, OHIO.

CARBURETOR.

Application filed July 18, 1919. Serial No. 311,755.

The present invention relates to carburetors.

The object of the invention is to provide a carburetor so constructed and organized as to produce a thoroughly vaporized mixture of fluid fuel and air.

A further object is to provide a carburetor which will efficiently take care of the heavier fuel oils, among which may be mentioned kerosene as well as the poorer grades of gasoline.

A further object is to provide a carburetor in which the supply of fuel mixture is presented to the manifold of the engine under pressure which is substantially constant.

Generally speaking, the invention may be said to comprise the elements and the combinations thereof set forth in the accompanying claims.

Reference should be had to the accompanying drawings forming a part of this specification in which Fig. 1 is an elevation with portions in section of a carburetor; Fig. 2 is a section upon the line 2—2 of Fig. 1; Fig. 3 is a section upon the line 3—3 of Fig. 1.

Referring to the drawings, 1 indicates a motor which is mounted upon a suitable casing represented at 2. This casing has an inner chamber indicated at 3. This chamber 3 communicates with the interior of an extension 4 which is carried by the casing 2. The relationship between the chamber 3 and the interior of the member 4 is such that air entering through the member 4 enters the chamber 3 in a tangential projection, thereby causing the air to swirl through the chamber 3 and be mixed with the fuel in a manner which will be later described.

The member 4 has associated herewith a butterfly valve 5 which may be positioned to regulate the quantity of air which may pass through the interior of the member 4.

At substantially the central portion of the chamber 3 there is an opening 6 which leads to a lower chamber 7 which is formed in the member 2. The chamber 7 is in part formed in the casing 2 and in part formed in the enclosure member 8 which is secured in the casing 2. The member 8 has an interior chamber portion 9 which communicates with the chamber 7.

The member 8 also has a wall 10 which is provided with an opening 11 and above the opening 11 there is placed a hollow screen member 12 so that all mixtures of

air and fuel passing from the chamber 9 must pass through the screen member 12. Below the wall 10 of the member 8 there extends a tubular portion 13 which may be formed in any suitable fashion so as to be connected with the intake manifold of an internal combustion engine.

The motor 1 is provided with a shaft 1^a, the shaft extending through the chamber 3 and through the opening 6. The shaft at its lower end carries a fan 14. This fan may be provided with any desired number of blades and the conformation of the chamber 7 is such that the fan occupies a substantial portion of the chamber and the diameter of the fan is but little less than the diameter of the chamber 7.

In the casing 2 an opening 15 is formed by drilling or otherwise (see Fig. 2), this opening communicating with the opening through the member 4. The casing is preferably formed with a threaded nipple 16 adjacent the opening 15 to which nipple may be secured a suitable pipe or conduit which in turn is connected with a source of liquid fuel.

In operation when the motor is started, it creates a certain amount of suction in the chamber 3 which induces air to flow through the member 4 and also induces the passage of fuel through the conduit 15 to mix with the air as it passes from the interior of the member 4 to the chamber 3.

As the air and fuel meet each other they are carried into the chamber 3 in a substantially tangential direction with respect to the walls of the chamber 3, thereby producing a whirling action which assists in mixing the air and the fuel.

From the chamber 3 the mixed air and fuel pass to the chamber 7 where they come in contact with the revolving fan blades. This causes a very thorough mixing of the air and fuel, and furthermore, any particles or globules of fuel are entirely broken up thereby securing a very thorough mixture as well as a thoroughly atomized mixture.

The air and fuel next pass to the chamber 9 and from the chamber 9 to the screen member 12 and thus to the manifold. The screen member 12 takes out any foreign substances which may be mixed with the air and fuel so that the mixture which passes through the screen 12 is in proper condition to pass to the internal combustion engine.

The mixture of air and fuel is delivered

to the chamber 9 under a certain amount of pressure which is induced by the fan and obviously the amount of pressure is a function of the speed of the fan.

5 Thus it will be seen that I may so operate the fan as to supply the fuel mixture to the engine under a positive pressure and not depend upon the suction of the engine, to induce the passage of fuel to the engine.

10 The construction which has just been described is entirely suitable for the purpose of making an effectively vaporized mixture of air and fuel but where the fuel may consist of the so called heavier oils, it is proposed to 15 make sure of their vaporization by providing that the mixture of air and fluid fuel shall be heated thereby to assist in obtaining a thorough vaporization of the fuel.

16 For this purpose I provide a heating element such as indicated at 18 in Fig. 1. This 20 heating element may consist of a coil of resistance wire such as indicated at 19 in Fig. 3, which coil is suitably imbedded in a non-conducting body such as indicated at 20. It 25 will be noted that this heating element 18 lies between the chamber 3 and the chamber 7 so that the mixture of air and fuel is heated in the chamber 3 and also in its passage through the opening 6 and in the chamber 7. In fact, as the mixture of fuel and air proceeds 30 through the chamber 3 and to the chamber 7 the mixture becomes quite thoroughly heated and it will be apparent the degree of heat which is applied to the 35 resistance coil 18 may be controlled so as to supply as much heat as may be required for the character of fuel which is being used.

40 The provision of a heating element such as described has a further use and advantage in that the mixture of air and fuel may be heated to a proper degree before introduction into the internal combustion engine with which it is used. This is particularly 45 advantageous in cold weather.

46 As will be apparent the motor may be operated at different speeds thereby to control the degree of pressure exerted on the atomized fuel and air passing from the carburetor, and additionally the speed of the 50 motor may be controlled to correspond with the variation and speed of the internal combustion engine with which it is used.

55 The motor may also have a connection which will permit its independent operation

so that the carburetor motor can be operated before the engine is started, thereby insuring a properly vaporized and heated fuel mixture under proper pressure which may be supplied to the engine at the time it is started.

60 In Fig. 1 a pipe 21 is shown as connected with the interior passage way through the member 4. This pipe 21 may be connected with the radiator for the combustion engine or some other suitable portion of the water circulating system thereby to admit a certain amount of moist air or steam along with the air which is taken into the carburetor.

65 I have also shown in Fig. 1 a pipe 22 which connects the chamber 3 with the chamber 9. This bypass connection is controlled by a valve 23. This valve may be controlled by the pressure in chamber 9, being operated to open the connection through the bypass 22 when the pressure in the chamber 9 exceeds that in the chamber 3.

Having described my invention, I claim—

70 1. A carburetor comprising a body member provided with a chamber having a central opening, an air inlet opening which communicates with the said chamber in a substantially tangential direction, a fuel inlet which communicates with the air inlet opening, a second chamber which communicates with the central opening from the first chamber, a heating member associated with both the said chambers, a pressure creating device located in the second chamber and means for positively driving said device, the said second chamber being provided with an outlet.

75 2. A carburetor comprising a casing, a chamber in said casing having a central outlet and air inlet to the casing which communicates with the said chamber in a substantially tangential direction, a fuel inlet in the casing which communicates with the air inlet adjacent the said chamber, a second chamber in the casing which communicates with the outlet of the first mentioned chamber, a fan located in the second chamber, a motor mounted upon the said casing, a motor shaft which extends through the said casing and supports the said fan, the said second chamber provided with an outlet.

80 In testimony whereof, I hereunto affix my signature.

ARTHUR M. SMITH.
